UNITED STATES PATENT OFFICE

154,910

DESIGN FOR AN EGG HOLDER

John J. De Luce, Minneapolis, Minn.

Application January 25, 1947, Serial No. 136,406

Term of patent 3½ years

(Cl. D44—4)

To all whom it may concern:

Be it known that I, John J. De Luce, a citizen of the United States, residing at Minneapolis, in the county of Hennepin, State of Minnesota, have invented a new, original, and ornamental Design for Egg Holder, of which the following is a specification, reference being had to the accompanying drawing, forming a part thereof.

Fig. 1 is an elevation of an egg holder with the two sections thereof spread apart showing my design;

Fig. 2 is an end elevation of the same with the sections closed in operative position; and

Fig. 3 is a fragmentary side elevation of the same with the sections closed in operative position.

The essential features of the design reside in the portions shown in full lines.

I claim:

The ornamental design for an egg holder, as shown and described.

JOHN J. DE LUCE.
